UNITED STATES PATENT OFFICE

WILLIAM S. TIMBLIN, OF RIVER FOREST, ILLINOIS

UMBRELLA

Application filed January 26, 1927. Serial No. 163,667.

This invention relates to new and useful improvements in umbrellas, more particularly to that type suitable for manufacture and sale at a low price for emergency purposes.

This invention has for one of its objects the provision of an improved emergency umbrella which may be manufactured at a low cost, is compact when folded, and takes a preferably rectangular form when folded, so that it may be readily placed in a coin-operated dispensing machine and delivered from such a machine, as required, in a form which readily permits of the opening and extending 15 of the umbrella for temporary use.

Other objects and advantages of this invention reside in the provision of an improved method of making an umbrella whereby the body of the article may be formed 20 from a single sheet of material cut and scored and suitably provided with connected portions whereby a substantially circular top which, when extended, including integral ribs, can be formed from a single rectangular 25 sheet of material.

Other objects of this invention reside in the provision of an umbrella formed of a single sheet of material having integral reinforcing portions forming ribs; the provision of an improved umbrella including a top portion and integral reinforcing ribs, which ribs are so formed as to facilitate folding of the umbrella into a substantially rectangular form; and the provision of an improved umbrella of the character referred to, 35 having an improved form of handle construction for maintaining the umbrella extended in use.

The foregoing and such other objects and 40 advantages as may appear or be pointed out as this description proceeds are attained in the structure shown in the drawings, in which:

Figure 1 is a bottom plan view of the umbrella in extended position; Figure 2 is a transverse sectional view taken on the line 2-2 of Figure 1 looking in the direction indicated by the arrows; Figure 3 is an enlarged transverse sectional view taken on the 45 line 3-3 of Figure 1 looking in the direction

indicated by the arrows; Figure 4 is a plan elevational view of the sheet from which the umbrella is formed; Figure 5 is an edge elevational view of the sheet shown in Figure 4; Figures 6 and 7 are perspective views of the sheet in various stages of formation; Figures 8 and 9 are elevational views illustrating the manner in which the umbrella is folded and Figure 10 is a perspective view showing the umbrella in its form folded. 55 60

Referring more particularly to the drawings, and as to Figures 1 and 2, the general form of the umbrella, when opened for use, is shown, the umbrella including the top portion 5 formed with a plurality of radial generally outwardly tapering ribs 6. The umbrella is supported by the handles 7 and 8 which are pivotally connected at 9 and 10 to the top by virtue of transverse pivots 11 and 12 passing through adjacent inner portions of the ribs 6. 65 70

The umbrella of this invention is preferably formed of a single sheet 13 of flexible material (see Fig. 4), such as heavy waterproofed paper or other suitable fabric, 75 said sheet being substantially rectangular in form and cut away at its end portions, as indicated at 14 and 15, to form projecting end flaps 16 and 17, one flap being adjacent one long edge 19 of the sheet and the other flap being adjacent to the edge 19^a, for a purpose which will presently appear. 80

The sheet thus formed is provided with a plurality of transverse scores 18 which latter are substantially perpendicular to the opposite edges 19 and 19^a of the sheet. The sheet is also provided with two series of diagonal scores 20 and 21, the individual scores in each being parallel to each other and crossing along the central longitudinal axis, the sheet also being scored longitudinally along said axis as indicated at 22. 85 90

The scores 20 and 21 provide a plurality of diamond shaped areas 23, 23 and each of said areas is provided with a central transverse score 24. 95

The diamond shaped areas 23, shaded as shown in Figure 4, are coated with a suitable adhesive composition, preferably waterproof, and the scores 24 are provided in such a 100

manner as to facilitate bending the sheet therealong to bring the adhesively coated halves of each diamond portion into contact, whereupon they are secured in this position under pressure to form a structure like that shown in Figure 6. In Figure 6 it will be seen that a pleated structure is formed, this being the position of the parts before the flaps 16 and 17 are secured to their complementary members of the group of pleats as will hereinafter appear.

It will be understood that the adhesive coating is applied to but one side of the sheet so that the other side is plain except for the 15 scoring.

The scores 24 are provided, to permit bending of the sheet, oppositely to the scores 17 so that, referring to Figure 6, the upper edges 24^a of the pleats correspond to the scoring 24 and the lower edges 18^a in Figure 6 correspond to the scoring 18. The structure shown in Figure 6 is then flattened into the form shown in Figure 7, by dividing the same at 25 into two groups 31 and 32 of pleats, and 20 the flap 16 is then attached in its entirety by suitable adhesive to the endmost pleat 26, that is, the opposite plain surface of the flap 16 from that shown in Figures 4 and 6 is connected to the exposed surface 26 shown in 25 Figure 6, and similarly the flap 17 is fixed, in its entirety, to the surface 27 of the endmost pleat 28.

This attachment of the flaps is accomplished by dividing the pleats at the point 25, 35 as shown in Figure 6, equally and spreading the same to the flat formation as shown in Figure 7, whereupon the exposed surface of the flap 16 is coated and is secured to the surface 26, and the flap 17 is similarly secured to the surface 27 by bending the structure on line 30, Figure 7. This structure, if slightly distended, will then appear as shown in Figures 8 and 9.

The latter structure thus formed, after being bent upon itself at 30 so that the flaps 16 and 17 are connected to their respective pleats, will appear as shown in Figure 10. This structure, such as that shown in Figures 8 and 9, slightly distended, includes the two groups 31 and 32 of pleats, connected by the intermediate portion 33 capable of being folded, as at 30. The connections between the flaps 16 and 17 and the adjacent pleats appear at the medial portion of the folded umbrella, as shown in Figures 8 and 10. The handles 7 and 8 are then inserted between adjacent pleats, preferably at substantially opposite points in the two groups 31 and 32, at 34 and 34^a as indicated in Figure 8, and the 40 article is then complete for use. It is shipped in a substantially rectangular form as shown in Figure 10 in a suitable envelope and may be dispensed in a desired quantity flat from a suitable dispensing coin-operated apparatus, if desired.

To open the article shown in Figure 10, the structure is held in a vertical position, as in Figure 9, and a thumb or forefinger of each hand is inserted, as indicated in Figure 9, at the point 35 on each side of the group of pleats to grasp one each of the handles. The handles being moved outwardly will bend the article along the score 36 (one of the scores 18) to separate the groups 31 and 32 of pleats outwardly. As the pleats are divided outwardly, the two portions 37 and 38 of the umbrella formed by the groups of pleats will abut, and the handle portions secured to said pleats will thereby come together and will serve to hold the structure extended. These two handles, as shown in Figure 2, are provided with recessed portions 39 and 40 which abut the adjacent portions 41 of the pleats where they are grouped and bent as shown in Figure 2, and by grasping both handles, the umbrella will be retained in the extended position.

By providing the diamond shaped portions, it will be seen that tapering ribs are afforded consisting of double thicknesses of paper, as indicated at 42 and 43, in Figure 3, the top 5 between adjacent ribs, owing to the scorings 18 being slightly raised so that when folding the pleats of the article nest properly. The portions 18, when the umbrella is folded, are presented toward each other, as indicated in Figure 10, and, as the umbrella is expanded in the manner shown in Figure 9 these portions 18 are presented outwardly or on the top side of the top of the umbrella.

Having thus described my invention and illustrated its use, what I claim as new and desire to secure by Letters Patent is:

1. A folding umbrella formed of a single blank of material including a plurality of pleats, said pleats being adhesively connected to form radial reinforcing members angularly related to the top when the umbrella is extended for use.

2. In a folding umbrella, a top portion formed of a single blank of flexible material, said blank being creased and folded to form a plurality of reinforcing portions, and a pair of cooperating handles hingedly connected to said reinforcing portions.

3. A folding umbrella including a top portion having reinforcing portions formed integrally therewith, and cooperating handles pivotally connected to said top and between said reinforcing portions and movable about the pivots so as to act as levers on the adjacent reinforcing portions of the umbrella and to maintain the top in extended position.

4. A folding umbrella including a substantially circular top portion having creases therein so that it may be folded into substantially rectangular configuration, reinforcing and supporting portions for said top, and handles pivotally connected to said reinforcing portions and receivable between and

housed by said portions when the umbrella is folded.

5. A folding umbrella including a top formed with a plurality of radial integral ribs, and a pair of supporting handles at the center of said top and hingedly connected thereto between adjacent ribs.

6. An article of manufacture including a sheet of flexible material creased to form a series of contiguous diamond shaped portions and alternate triangular shaped portions, said diamond shaped portions being coated with an adhesive.

7. An article of manufacture including a sheet of flexible material creased to form a series of contiguous diamond shaped portions and alternate triangular shaped portions, said diamond shaped portions being coated with an adhesive, and a plurality of creases, one each extending along the longitudinal axis of each of said diamond shaped portions whereby the adhesively coated portions thereof may be connected.

8. The process of forming a substantially circular sheet from a substantially rectangular sheet which includes the steps of forming symmetrical transverse diagonal creases and folds in said sheet, and connecting portions of each of said folds.

30 9. The process of forming a substantially circular sheet from a substantially rectangular sheet which includes the steps of forming symmetrical transverse diagonal creases and folds in said sheet, and connecting portions of each of said folds, and then expanding said folds in opposite directions, and connecting the complementary end portions of the sheet.

10. The process of forming a substantially circular sheet from a substantially rectangular sheet of flexible material which includes the steps of transversely creasing said sheet along parallel and diagonally arranged lines and also along parallel lines normal to the edges of the sheet, bending the sheet along said lines to form pleats, and connecting adjacent portions of the surfaces defined by said diagonal lines to afford tapering reinforcing portions.

50 11. The process of forming a substantially circular sheet from a substantially rectangular sheet of flexible material which includes the steps of transversely creasing said sheet along parallel and diagonally arranged lines and also along parallel lines normal to the edges of the sheet, bending the sheet along said lines to form pleats, and adhesively connecting adjacent portions of the surfaces defined by said diagonal lines and forming said pleats to afford tapering reinforcing portions.

60 12. A folding umbrella including a top foldable into two halves and adapted, when opened, to bring said halves into substantially the same plane, and a pair of handles,

one of which is supported by one of said halves and the other of which is supported by the other of said halves and which handles may also be brought into juxtaposition when said umbrella is opened, whereby the umbrella may be held in open position, said two halves being provided with reinforcing ribs and said handles being pivoted to said halves between said ribs.

13. An umbrella including a top body portion and radial reinforcing portions constructed of a substantially plane piece of material, said material having creases therein so as to double fold the same to form multiple plies in said reinforcing portions, and said plies having their adjacent surfaces connected for rigidifying the same.

14. A folding umbrella including a substantially circular top portion comprising a substantially plane and substantially rectangular sheet of flexible material provided with transverse and diagonal creases whereby it may fold to bring the same to substantially circular form.

15. A folding umbrella including a top foldable into two halves and adapted, when opened, to bring said halves into substantially the same plane, and a pair of handles, one of which is pivotally supported by one of said halves and the other of which is pivotally supported by the other of said halves and which handles are angularly displaceable to be brought into juxtaposition when said umbrella is opened, said handles thereby engaging a portion of each half whereby the umbrella may be held in open position.

16. An umbrella comprising a flexible top having a circumferentially continuous edge, a plurality of pleats in said top forming reinforcing rib members for supporting said top formed integrally therewith, said rib members being grouped to form angularly displaceable portions of the top and said groups being disconnected from each other whereby the top and said ribs may be turned inside out and folded.

17. An umbrella including a top body portion formed of a plurality of flexible sections interconnected by contiguous integral flanges disposed at substantially right angles to the top when spread, said flanges forming radial multiple-ply reinforcing ribs for said top.

18. An umbrella including a top body portion formed of a plurality of flexible sections interconnected by contiguous flanges disposed at substantially right angles to the top when spread, and means secured between certain flanges for maintaining the top spread.

19. An umbrella including a top body portion formed of a plurality of flexible sections interconnected by contiguous flanges disposed at substantially right angles to the top when spread, and means secured between certain flanges for maintaining the top spread,

- said means being received between flanges when the umbrella is folded.
20. An umbrella including a top body portion formed of a plurality of flexible substantially rectangular sections interconnected by contiguous flanges disposed at substantially right angles to the top when spread. 70
21. An umbrella including a top body portion formed of a plurality of flexible sections 10 formed with contiguous reinforcing portions fixedly connected together, said reinforcing portions being adhesively connected to form radial ribs lying at an angle to said top.
22. An umbrella including a top body portion formed of a plurality of flexible sections 15 formed with contiguous reinforcing portions fixedly connected together, said reinforcing portions lying at right angles to the plane of the top and being tapered from the center of 20 the top toward the edge thereof.
23. An umbrella including a top body portion formed of a plurality of flexible sections having marginal contiguous flanges fixedly connected to form multiple ply reinforcing 25 members lying at an angle to said top.
24. A folding umbrella including a substantially circular top portion adapted to be folded into substantially rectangular configuration, including a plurality of substantially rectangular flexible sections having each marginal flanges fixedly connected together to 30 form reinforcing and supporting portions for said top, and handles pivotally connected to said reinforcing portions and receivable between and housed by said portions when the umbrella is folded. 95
25. A folding umbrella including a substantially circular top creased and folded to provide angularly disposed ribs and connecting areas therebetween, a handle pivoted to 40 and for supporting the umbrella in open position, the creases in said top being so arranged that when the latter is folded it takes a rectangular form with said ribs and handle within the outline thereof. 100
26. An umbrella including a top body portion formed of a plurality of flexible sections interconnected by contiguous integral flanges disposed at substantially right angles to the 50 top when spread, said flanges forming radial multiple-ply reinforcing ribs for said top. 110
27. An umbrella including a top body portion formed of a plurality of flexible sections interconnected by contiguous flanges disposed at substantially right angles to the top when spread, and means secured between certain flanges for maintaining the top spread. 115
28. An umbrella including a top body portion formed of a plurality of flexible sections 60 interconnected by contiguous flanges disposed at substantially right angles to the top when spread, and means secured between certain flanges for maintaining the top spread, said means being received between flanges 120 when the umbrella is folded. 130
29. An umbrella including a top body portion formed of a plurality of flexible substantially rectangular sections interconnected by contiguous flanges disposed at substantially right angles to the top when spread. 70
30. An umbrella including a top body portion formed of a plurality of flexible sections formed with contiguous reinforcing portions fixedly connected together, said reinforcing portions being adhesively connected to form radial ribs lying at an angle to said top. 75
31. An umbrella including a top body portion formed of a plurality of flexible sections formed with contiguous reinforcing portions fixedly connected together, said reinforcing portions lying at right angles to the plane of the top and being tapered from the center of the top toward the edge thereof. 80
32. An umbrella including a top body portion formed of a plurality of flexible sections having marginal contiguous flanges fixedly connected to form multiple ply reinforcing members lying at an angle to said top. 85
33. A folding umbrella including a substantially circular top portion adapted to be folded into substantially rectangular configuration, including a plurality of substantially rectangular flexible sections having each marginal flanges fixedly connected together to form reinforcing and supporting portions for said top, and handles pivotally connected to said reinforcing portions and receivable between and housed by said portions when the umbrella is folded. 90
- In testimony whereof, I have hereunto signed my name.
- WILLIAM S. TIMBLIN.
